JOSEPH SNYDER, OF ROCK LICK, WEST VIRGINIA.

Letters Patent No. 74,441, dated February 11, 1868.

IMPROVEMENT IN CULTIVATORS.

The Schedule referred to in these Letters Patent and making part of the same.

TO ALL WHOM IT MAY CONCERN:

Be it known that I, JOSEPH SNYDER, of Rock Lick, in the county of Marshall, and State of West Virginia, have invented a new and useful Improvement in Cultivators; and I do hereby declare that the following is a full, clear, and exact description of the same, reference being had to the accompanying drawings, making a portion of this specification, in which—

Figure 1 is a side view and partial section of a cultivator made according to my invention.

Figure 2 is a plan view of the same.

Similar letters of reference indicate corresponding parts in both figures.

This invention consists in a novel construction of a cultivator, whereby the same is made very strong and durable, and also very efficient in operation.

To enable others to understand the nature and construction of my invention, I will proceed to describe it with reference to the drawings.

A indicates the main beam of the implement, to the forward end of which may be attached a link or clevis, a, and the rearmost portion of which is bent downward, as shown at b, with a triangular or other properly-shaped share, c, bolted to the extremity thereof. Shown at B is a supplemental beam, firmly bolted at its forward end to the side of the main beam, and situated at an angle thereto, as represented more plainly in fig. 2. This supplemental beam does not extend back as far as the main beam, but it has its rearmost end bent or turned downward in the same manner as the aforesaid main beam, and furnished with a similar share, d. Attached in any suitable manner to the two sides of the main beam, are the two handles, C, which may be made of wrought-iron bars, and which, extending obliquely back and upward, terminate in appropriate handle-pieces, e. The back portions of the two handles, C, are connected by a cross-brace, f, and extending downward therefrom to the rear part of the main beam, are two oblique strengthening-braces, g. An additional brace, m, extends from one of the handles, C, to the contiguous end of the supplemental beam B, and serves to stiffen or support the same against any lateral strain exerted thereon.

As thus constructed, the cultivator is very strong, and consequently very durable, and little liable to get out of repair, and may, furthermore, be manufactured at a very moderate cost; and is also very light, and convenient to handle when in use.

What I claim as my invention, and desire to secure by Letters Patent, is—

The cultivator, constructed with the curved main beam A, and curved supplemental beam B, shares c d, handles C, and braces f, g, and m, the whole arranged substantially as and for the purpose specified.

JOSEPH SNYDER.
